UNITED STATES PATENT OFFICE

111,998

DESIGN FOR A GUIDE CHART OR SIMILAR ARTICLE

Samuel J. Sigaloff, Long Island City, N. Y.

Application June 29, 1938, Serial No. 78,143

Term of patent 3½ years

To all whom it may concern:

Be it known that I, Samuel J. Sigaloff, a citizen of the United States, residing at Long Island City, in the county of Queens and State of New York, have invented a new, original, and ornamental Design for a Guide Chart or Similar Article, of which the following is a specification, reference being had to the accompanying drawing, forming part thereof.

In the drawing

Fig. 1 is a top plan view of a guide chart showing my new design; and

Fig. 2 is an edge view thereof.

The design of my guide chart is characterized by the scalloped edges of a smaller disc and a larger disc divided adjacent its periphery into sections with pointed indicators at the center portions thereof.

I claim:

The ornamental design for a guide chart or similar article, substantially as shown and described.

SAMUEL J. SIGALOFF.
